Primary Examiner—Holly Baynham*Attorney, Agent, or Firm*—William W. Haefliger[57] **CLAIM**

The ornamental design for a vehicle mount for portable compact disc player, as shown and described.

DESCRIPTION

FIG. 1 is a left side elevation view of a vehicle mount for portable compact disc player with the right view being a mirror image;

FIG. 2 is a rear elevation view;

FIG. 3 is a front elevational view.

The cable element of the claimed design is shown broken away to indicate indeterminate length.

The support is shown separately for clarity of illustration. The top and bottom plan views of the vehicle mount for a portable compact disc player form no part of the claim design.
